UNITED STATES PATENT OFFICE.

FRANK J. PERRON, OF AURORA, ILLINOIS, ASSIGNOR TO NATIONAL BRUSH COMPANY,
A CORPORATION OF ILLINOIS.

SHOE-CLEANING DEVICE.

1,124,650.

Specification of Letters Patent. Patented Jan. 12, 1915.

Application filed October 11, 1913. Serial No. 794,584.

To all whom it may concern:

Be it known that I, FRANK J. PERRON, a citizen of the United States of America, and a resident of Aurora, county of Kane, and 5 State of Illinois, have invented certain new and useful Improvements in Shoe-Cleaning Devices, of which the following is a specification.

The main objects of this invention are to 10 provide an improved device for removing from shoes mud and dirt that may be accumulated thereon; to provide a device of this kind having means adapted to be used for first scraping the mud from the shoes and 15 then wiping the bottom and sides of the shoes; to provide an improved arrangement of the wiping means; and to provide improved means for supporting the wiping means in position.

20 An illustrative embodiment of this invention is shown in the accompanying drawings, in which—

Figure 1 is a perspective view of the shoe 25 cleaning device. Fig. 2 is the bottom plan view of the same.

In the construction shown in the drawings the device comprises a supporting member or frame 3, having a scraper 4 at the forward end thereof, and shoe wiping means 5 30 at the other end. The scraper 4 is in the form of an angle plate secured to the frame 3 by suitable screws 6. The shoe wiping means 5 comprises a bottom brush 7 formed on the upper side of the frame 3 and extending 35 the greater portion of its length. Other brushes 8 are mounted at the sides of said bottom brush 7 and have the bristles 9 thereof arranged above the plane of the bristles of the brush 7 and overlapping the edges 40 thereof. A pair of V-shaped members 10 and 11 formed of resilient wire are secured to the under side of the frame 3 by means of staples 12 located at the crotches of said members. The members 10 and 11 are arranged 45 as shown in Fig. 2 so that the respective arms thereof are substantially parallel. The outer ends of the arms of the members 10 and 11 are bent outwardly to form the bends 13 and then upwardly at the sides 50 of frame 3 to form the bends 14. The brushes 8 are secured to the upwardly disposed bends 14 by being inserted into suitable apertures formed in the backs of said brushes. This parallel arrangement of the

arms of the members 10 and 11 permits the 55 brushes 8 to yield more at one end than the other as the shoe enters or recedes from the brushes so that the wiping of the brushes will be more effective than if it were necessary for them to remain in parallel relation 60 when urged outwardly. The frame 3 is provided with suitable apertures 15 through which fastening means may be passed for securing the device in position to be used.

The device is used in the following manner: When it is desired to remove the accumulations of dirt or mud from a shoe the wearer first scrapes the shoe on the scraper 4 and as he does so draws the shoe rearwardly between the brushes 8 and over the brush 7 70 so that the sole and sides of the shoe are wiped clean. As the heel of the shoe enters the space between the brushes 8 they will yield first at the forward ends as indicated in dotted outline in Fig. 2, and then as the 75 shoe continues to pass along the brushes the rear ends thereof will also be urged outwardly. As the toe of the shoe recedes from the brushes the forward ends thereof will be the first to return to their normal positions 80 followed by the rear ends. This action of the brushes 8 insures that a greater portion of the shoes is cleaned than is the case when the parallel relation of the brushes remains constant.

Although but one specific embodiment of this invention has been herein shown and described, it will be understood that some of the details of the construction shown may be altered or omitted without departing from 90 the spirit of this invention as defined by the following claims.

I claim:

1. A shoe cleaning device comprising a frame, a brush on the bottom of said frame, 95 other brushes located at the sides of said bottom brush, a plurality of V-shaped members arranged on the under side of said frame with the corresponding arms arranged in substantially parallel relation, and extending lengthwise of said frame, the outer ends of said arms being bent transversely outward and then upward, the upwardly disposed parts being attached in pairs to said side brushes.

2. A shoe cleaning device comprising a frame, a brush on the bottom of said frame, other brushes located at the sides of said

bottom brush, a plurality of V-shaped members arranged on the under side of said frame and nested one within the other with the corresponding arms arranged in substantially parallel relation, means securing said V-shaped members at the crotch thereof, the outer ends of said arms being bent transversely outward and then upward, the

upwardly disposed parts being attached in pairs to said side brushes.

Signed at Aurora this 7th day of October 1913.

FRANK J. PERRON.
